United States Patent Office

Des. 211,800
Patented July 30, 1968

211,800

GOLF CLUB HEAD

Charles G. Hunter, 57835 Yucca Trail,
Yucca Valley, Calif. 92284

Filed Nov. 22, 1967, Ser. No. 9,511

Term of patent 14 years

(Cl. D34—5)

FIG. 1 is a vertical view looking into the striking face of the golf club head showing my new design;

FIG. 2 is a top view of FIG. 1;

FIG. 3 is a left-hand end view of FIG. 1;

FIG. 4 is a bottom view of FIG. 1; and

FIG. 5 is a right-hand end view of FIG. 1.

The broken lines indicating a shaft are for illustrative purposes only.

I claim:

The ornamental design for a golf club head, as shown and described.
